UNITED STATES PATENT OFFICE

2,560,405

APPARATUS FOR SETTING UP CARTONS

Leonard Back, Middletown, Ohio, assignor to The Interstate Folding Box Company, Middletown, Ohio, a corporation of Ohio

Application March 30, 1949, Serial No. 84,445

18 Claims. (Cl. 93—51)

1
The primary object of my invention is the provision of a simple and inexpensive apparatus for the erection of one-piece cartons and the holding of the erected structure in position during filling and prior to the interengagement or securing of flaps which will maintain the carton as a complete closure for its contents. My apparatus is especially useful for one-piece cartons of a type having a main panel, side and end walls articulated to the panel, bellows folding corner connecting portions between the respective ends of the side and end walls, and a plurality of flaps articulated to the outer edges of the side and end walls and coacting, in the closed container, to form a sixth wall. Cartons of this type do not maintain their erected condition until the folding over of the last mentioned flaps and the securing of them to form the sixth wall. While the utility of my invention is not confined thereto, I will describe its use in connection with a type of carton described in the copending application of Robert M. Bergstein, Serial No. 62,257, filed November 27, 1948, and entitled Lined Box Structures and Method of Making Them.

Another object of my invention is the provision of a new and simplified means for insuring the positioning of the folded corner connecting webs inside the erected carton and lying against predetermined walls, so as not to interfere with the filling of the contents into the cartons.

Another object of my invention is to provide in a simple mechanism a series of rapid but correlated operations in setting up cartons of this class, and to provide simple but positively acting mechanism for correlating these operations.

These and other objects of the invention, which will be set forth hereinafter or will be apparent to one skilled in the art upon reading these specifications, I accomplish by that construction and arrangement of parts of which I shall now describe an exemplary embodiment. Reference is made to the accompanying drawings wherein:

Figure 1 is a plan view of my mechanism with certain parts cut away, and is related to the line 1—1 of Figure 2.

Figure 2 is a vertical sectional view of the apparatus taken along the section line 2—2 of Figure 1.

Figure 3 is a partial vertical sectional view taken along the line 3—3 of Figure 2.

Figure 4 is a partial perspective view of one of my corner web engaging means.

Figure 5 is a partial elevational view showing the face of my plunger, and is related to the line 5—5 of Figure 2.

Figure 6 is a vertical sectional view of the apparatus, similar to that of Figure 2 but showing the plunger at the start of an operating stroke.

Figure 7 is a partial elevational view of the end of a pull-rod member.

2
Figure 8 is an elevational view of a cam plate and latch mechanism employed in controlling the lower plunger.

Figure 9 is an edge view thereof.
5 Figure 10 is a partial sectional view related to the showing of Figure 6, but illustrating the position of the parts at the completion of the stroke of the upper plunger.

Figure 11 is a similar view after the upward stroke of the upper plunger, showing the lower plunger maintained in its downward position.

Figure 12 is a partial perspective view showing the relationship of a carton blank to my mechanism at the start of the setting up operation.
10 Figure 13 is a similar view illustrative of the initial folding.

Figures 14, 15 and 16, related to the section line 14—14 of Figure 13, are successive sectional views illustrative of the folding of the blank during the descent of the upper plunger.

Figures 17 and 18, related to the section line 17—17 of Figure 13, are successive sectional views illustrating the relationship of the carton to the machine when the carton is in the set-up but unclosed condition and is ready for filling.

20 Figure 19 is a partial perspective view showing the relationship of the carton to the machine when the carton is in filled and closed condition.

Figure 20 is a similar view showing the filled and closed carton as released by the upward movement of the lower plunger.

Referring first to Figures 1 to 3 inclusive, my machine comprises a base 4 and an upper platform 6 which is supported above the base. This may conveniently be done by passing bolts 7 through the base and platform at the corners of each, and surrounding the bolts with hollow metallic sleeves 8 located between the base and platform and serving to separate them the required distance.

35 Figure 21 is a plan view of my mechanism with certain parts cut away, and is related to the line 1—1 of Figure 2.

Figure 22 is a vertical sectional view of the apparatus taken along the section line 2—2 of Figure 1.

Figure 23 is a partial vertical sectional view taken along the line 3—3 of Figure 2.

Figure 24 is a partial perspective view of one of my corner web engaging means.

Figure 25 is a partial elevational view showing the face of my plunger, and is related to the line 5—5 of Figure 2.

Figure 26 is a vertical sectional view of the apparatus, similar to that of Figure 2 but showing the plunger at the start of an operating stroke.

lower plunger are accomplished and controlled by means hereinafter set forth.

At the rear of the platform 6, I provide rearwardly extending, spaced bracket elements 16 and 17, conveniently though not necessarily in the form of angle irons bolted to the platform. Near the rear ends of these brackets I pivot as at 18 and 19 a pair of bar elements 20 and 21. As shown in Figure 2, the upper ends of these bar elements are angularly disposed as at 21a, 10 and the vertices of the angles of the two bars 20 and 21 are interconnected by an element 22 which, in a hand operated machine, will serve as an operating handle.

The outer ends of the angularly related portions 20a and 21a of the bar elements (see Figure 5) are pivoted to brackets 23 and 24 which are attached to a member 25 serving as an upper plunger. The relationship of the parts is such that when the bar elements 20 and 21 are swung downwardly on their pivots 18 and 19, the upper plunger element 25 will coincide with the lower plunger element 10. The upper plunger element is substantially congruent to the lower plunger element, and both are very slightly smaller than the main panel of the carton to be erected. However, corner portions of the upper plunger 25 are slightly recessed as shown at 25a.

To urge the bar elements and upper plunger to their upper positions, I provide upstanding elements 26 and 27 on the brackets 16 and 17, and engage tension springs 28 and 29 between the upper ends of these elements and ears 30 and 31 on a shaft 32 extending across between the lower ends of the bar elements 20 and 21. Stops to limit the motion of the bar elements to a substantially vertical position are provided, and these may conveniently take the form of angular abutments 33 and 34 welded or otherwise attached to the brackets 16 and 17.

Referring to Figures 8 and 9, I provide a segment-shaped cam plate 35, having cam opening 36 therein; and I pivot this cam plate to a bracket 37 on the plate 11, as shown in Figures 2, 3, 6, 10 and 11. The cam opening in the plate has a cam surface 38 terminating downwardly in a recess 39 for a purpose hereinafter described. The lower plunger 10 is provided with a downwardly depending bracket 40, having a laterally extending pin 41 engaging in the cam opening 36 of the cam plate 35 and acted upon by the cam surface thereof. A strap element 42 is welded or otherwise fastened at its ends to the cam plate 35 and extends across the cam opening 36 as shown in Figure 8. It lies on the side of the cam plate opposite the bracket 40. The strap element 42 carries a laterally extending pin 43 which is connected by a tension spring 44 to a bracket 45 on the base 4. The spring tends to urge the cam plate 35 in a clockwise direction, as shown in Figures 2, 6, 10 and 11.

An elongated pull rod 46 is pivoted to the shaft 32 which interconnects the lower ends of the bar elements 20 and 21. This pull rod extends forwardly in the machine beneath the platform 6. As shown in Figure 7, its forward end has a downwardly extending enlargement providing a shoulder or detent 47. This detent is adapted under certain circumstances to engage the laterally extending pin 43 on the strap element 42 hereinabove described. But with the cam plate in its upright position as illustrated in Figures 2 and 6, the forward end of the pull rod is supported by a pin 48 on the cam plate. When the bar elements 20, 21 lie in the position

shown in Figure 2, the detent 47 of the pull rod 46 will lie to the right of the pin 43 as will be evident. If the bar elements 20, 21 are swung downwardly as in Figure 6, the pull rod 46 will move to the left, but because the forward end of the pull rod is supported by the pin 48, the detent 47 will not engage the pin 43 but will pass beyond it to the left. A continuation of the downward movement of the bar elements 20, 21, as produced, for example, by a pull on the handle 22, will cause the upper plunger 25 to engage the lower plunger 10 and depress it against the compression of the springs 15. When the lower plunger is so depressed, as illustrated in Figure 10, the cam plate 35, hitherto maintained in upright position by the engagement of the pin 41 with its cam surface 38, will be rotated clockwise until the pin 41 engages in the recess 39 of the cam plate. This locks the lower plunger 10 in its lowermost position. If the bar elements 20, 21 are now swung upwardly, the upper plunger 25 will be raised; but the lower plunger 10 will remain in a depressed position, as illustrated in Figure 11. The cam plate pin 48 has been swung downwardly, and no longer supports the forward end of the pull rod 46. As a consequence, the rod can slide forwardly, resting upon the pin 43 until the detent 47 passes to the right of that pin.

However, if the operating handle 22 is now grasped, and the bar elements 20, 21 swung slightly downwardly, the detent 47 on the pull rod 46 engaging the pin 43 will move the cam plate 35 in a counterclockwise direction. This will serve to unlock the lower plunger element 10, by releasing the pin 41 from the recess 39. The rising motion of the lower plunger 10 as produced by the compression springs 15 will nevertheless be controlled by the engagement of the pin 41 with the cam surface 38, so that the operator of the machine can control this rising motion by means of the handle 22. The relationship of parts is such that while a full downward swing of the bar elements 20, 21 is necessary to cause the upper plunger 25 to contact and depress the lower plunger 10 to its lowermost position, whereupon the bar elements can be raised to their uppermost position with the lower plunger remaining depressed, a slight subsequent forward or downward movement of the handle 22 and a return of it to its uppermost position will release the lower plunger 10, and control its rise.

Adjacent the opening 8 in the platform 6, I provide elements indicated in Figure 1 at 49, 50, 51 and 52. These elements are conveniently formed from angle stock. As shown in Figure 4, their bases 49a may be provided with slots 53 for adjustment on screws or bolts which hold them to the platform 6. Their upstanding pins 49b are provided with shoulders 54 having a substantially vertical portion, a horizontal extending portion for supporting a blank and downwardly slanting front portions 55. These elements are so disposed on the platform 6 that their downwardly slanting portions 55 substantially coincide with the diagonal score lines in the corner connecting webs of blanks such as hereinafter described. The shoulders 54 are so located as to engage the outer edge portions of these corner connecting webs so that, among other functions, the elements 49, 50, 51 and 52 provide a means for locating carton blanks above the platform 6 in a proper position to be acted upon by the plungers. Also, at suitable

positions spaced from the opening 9 in the platform 6, I provide hold-down elements for end wall flaps of the blank. These hold-down elements are indicated at 56 and 57 and comprise arms 56a and 57a raised above the platform and extending in the direction of the opening 9, as will be clear from Figures 1 and 3. The bases of these elements may be provided with slots for adjusting their positions upon loosening the screws or bolts which hold them to the platform.

One form of carton blank with which my machine may be employed is shown in Figures 12, 13 and 17 to 19. Dot-dash lines in these figures indicate lines of score in a paperboard element. The exemplary blank comprises a main panel 58, end walls 59 and 60 articulated to the ends of the main panel, and side walls 61 and 62 articulated to its side edges. Between the respective ends of the side and end walls there are diagonally scored corner connecting webs 63, 64, 65 and 66. A pair of inner closure flaps 67 and 68 are articulated to the end walls 59 and 60. An intermediate closure flap 69 is articulated to the side wall 62 and an outer closure flap 70 is articulated to the side wall 61. In the particular blank these flaps are generally triangular in formation; but the flaps 69 and 70 are so shaped as to lap the flaps 67 and 68 when the box is in the closed condition. Tongues 71 and 72 may be formed on the flap 69 for engagement in slots 73 and 74 in the inner closure flaps; and the outer closure flaps 70 may be provided with a tongue 75 for engagement in a slot 76 substantially coinciding with the score line of the flap 69.

The main panel 58 of the carton may be provided with a window 77, and a single sheet of lining material, such as a grease-proof glassine paper or a transparent film may be applied to the blank so as to cover the main panel, the side and end walls, the corner connecting webs and such portions of the closure flaps 67, 68, 69 and 70 as will result in a completely lined box.

The carton illustrated herein is one suitable for setting up on my machine, but the utility of my machine is not confined thereto. The specific shapes of the closure flaps and corner connecting webs are not a limitation on the utility of this invention. While I have described a machine constructed to set up a carton of a particular size, it will be understood that if desired adjustable or replaceable parts may be provided to adapt the machine to cartons of different sizes. Also, while I have described a machine intended for hand operation in setting up cartons as an adjunct to hand filling operations for the cartons, power may be applied to the machines and, if desired, automatically acting means, known in the art, may be provided to supply the blanks to the machines.

The operation of my machine in setting up cartons will now be described. The carton is placed on the machine as illustrated in Figure 12, where it is located by the elements 49, 50, 51 and 52, and supported by the shoulders of these elements somewhat above the platform 6. The outer ends of the inner closure flaps 67 and 68 are engaged beneath the hold-downs 56 and 57. In its uppermost position the plunger 10 underlies the main panel 58 of the carton blank. In actual practice, as illustrated in Figures 2 and 6, the lower plunger 10 has an upper position slightly above the top surface of the platform 6.

With the carton in the position shown in Figure 12, the handle 22 of the machine is grasped and pulled forwardly to lower the plunger 25

into contact with the main panel 58 of the carton. A further depression of the upper plunger 25 will move the main carton panel 58 downwardly into contact with the lower plunger element 10 where it will be securely clamped between the two plunger elements. This clamping action permits a sharp folding along the score lines which outline the main body panel 38 as the carton blank is moved downwardly 10 into the female die.

But before the carton blank fully enters the female die, its corner connecting webs ride down the downwardly slanting portions 55 of the elements 49, 50, 51 and 52. This starts the corner 15 connecting portions bending along their diagonal score lines, and also starts an upward folding movement of the side walls 61 and 62. But by reason of the hold-downs 56 and 57 engaging the flaps 67 and 68, the upward folding movement 20 of the end walls 59 and 60 is delayed. Thus the diagonally scored corner connecting webs 63, 64, 65 and 66 begin to fold essentially behind the ends of the upper plunger element 25, and engage beyond the ends of this element in the 25 recess 25a before the upward folding movement of the end walls 59 and 60 begins or has progressed to any great extent.

As shown in Figure 14, after the main panel has been clamped between the lower plunger element 10 and the upper plunger element 25, a continued downward movement of the latter depresses the lower plunger element still further. Side and end edge portions of the opening 9 in the platform 6 engage and fold inwardly the 30 side and end walls 59, 60, 61 and 62. The lower plunger element 10 ultimately is depressed to a position well below the top surface of the platform 6, as shown in Figure 15, and the side and end walls of the box are folded to fully upright positions. Whereas the side walls 61 and 62 begin to fold first with concurrent folding of the corner connecting webs as shown in Figure 13, while the flaps 67 and 68 are held by the hold-downs 56 and 57, as the plunger elements 10 and 25 move further downwardly together, the flaps 40 45 67 and 68 move inwardly beneath the hold-down arms until their ends are reached, whereupon they pull out from under the hold-downs. The hold-downs may be adjusted to increase or decrease the delaying action. The corner connecting webs fold themselves completely and lie in the recesses 25a at the end of the upper plunger element, and the box assumes the erected but unclosed condition illustrated in Figures 16 and 17.

The lower plunger element 10 is locked in its lowermost position by the cam element described above. At this stage the handle 22 may be raised, 60 swinging the upper plunger 25 out of the erected carton and carrying it out of the way above the platform 6. By reason of the frictional engagement of the side and end walls of the carton with the edges of the opening 9 in the platform 6, the box will remain in the position shown in 65 Figures 16 and 17. The box may now be filled with its contents by the operator while held in the recess in the platform 6 in the erected but non-self-sustaining condition, as will be evident. Boxes of this general type are particularly useful for food products, such as foods to be frozen, meat products and the like, but their use is by no means so limited. However, it will be noted

that the box is maintained in erected condition in a convenient condition for filling. After the introduction of the contents, the box is closed,

as illustrated in Figure 18. This is accomplished with the particular exemplary embodiment by folding over the inner closure flaps 67 and 68, thereupon folding over the intermediate flap 69 and engaging the tongues 71 and 72 in the slots 73 and 74. After this, the outer closure flap 70 is folded over upon the intermediate flap and the tongue 75 is tucked into the slit 76. The box is now fully closed and fully self-sustaining.

During the filling operation the handle 22 has been at its highest position, the pull rod 46 is in its forward position, and the detent 47 hereinabove described is in a position to catch and engage the pin 43 on the strap of the cam plate. A slow forward pull on the handle 22 first accomplishes the release of the lower plunger element 10, and afterward the return of the handle controls (by means of the cam surface 38) the rise of this plunger. The plunger rises, as hereinabove indicated, to a position somewhat above the top surface of the platform 6 thus releasing the box, as shown in Figure 19, so that it may readily be removed from the machine. When the handle 22 has been returned to its uppermost position, the machine is set for the reception of another blank for erection. The new blank is positioned by means of the elements 49, 50, 51 and 52, and the operations hereinabove described are repeated.

Modifications may be made in my invention without departing from the spirit of it. Having thus described my invention in an exemplary embodiment, what I claim as new and desire to secure by Letters Patent is:

1. In a machine for setting up cartons of a type having a main panel, side and end walls articulated thereto, and diagonally scored corner connecting webs between the ends of the side and end walls respectively, a platform having an opening responding in size and shape to said main panel, whereby folding of the side and end walls with respect to said main panel will occur as said main panel is depressed into said opening, and means on said platform for engaging and locating a carton blank with its main panel above said opening, said means comprising elements having shoulders and downwardly extending edges and disposed on said platform so that the downwardly extending edges substantially coincide with the diagonal score lines in the corner connecting webs of said carton blank, said shoulders comprising horizontally extending portions for supporting the blank in a position above the upper surface of the platform and vertically extending portions for locating the main panel of the blank over the opening in said platform, said downwardly extending edges serving as score-breakers for the diagonal score lines in said corner connecting webs.

2. In a machine for setting up cartons of the type having a main panel, side and end walls articulated thereto, and diagonally scored corner connecting webs between the ends of the side and end walls respectively, a platform having an opening responding in size and shape to said main panel, whereby folding of the side and end walls with respect to said main panel will occur as said main panel is depressed into said opening, a depressible plunger operating against said main panel from above for depressing said main panel into said opening, and means on said platform for engaging and locating a carton blank with its main panel above said opening, said means comprising elements having shoulders and downwardly extending edges and disposed on the plat-

form so that the downwardly extending edges substantially coincide with the diagonal score lines in the corner connecting webs of the blank, said shoulders comprising horizontally extending portions for engaging and locating the blank in a position above the upper surface of the platform and vertically extending portions for locating the main panel of the blank above the opening in said platform, said downwardly extending edges being disposed slant-wise and serving as score-breakers for the diagonal score lines in said corner connecting webs.

3. In a machine for setting up cartons of the type having a main panel, side and end walls articulated thereto, and diagonally scored corner connecting webs between the ends of the side and end walls respectively, the platform having an opening responding in size and shape to said main panel, whereby folding of the side and end walls with respect to said main panel will occur as the main panel is depressed into said opening, means for depressing said main panel into said opening, means on said platform for engaging and locating a carton blank with its main panel above said opening, said means comprising elements having shoulders and downwardly extending edges and disposed on the platform so that the downwardly extending edges substantially coincide with the diagonal score lines of the corner connecting webs of said blank, said shoulders comprising horizontally extending portions for engaging and supporting the blank in a position above the upper surface of the platform and vertically extending portions for locating the main panel of the blank over the opening in the platform, said downwardly extending edges serving as score-breakers for the diagonal score lines in said corner connecting webs, and means on said platform for initially engaging portions of said blank and restraining the folding of an opposite pair of walls thereof, whereby during the depression of said main panel the other opposite walls begin to fold upwardly thereby starting the folding of said corner connecting webs in a position to lie against the first mentioned pair of opposite walls.

4. In a machine for setting up cartons of a type having a main panel, side and end walls articulated thereto, and diagonally scored corner connecting webs between the ends of the side and end walls respectively, a platform having an opening responding in size and shape to said main panel, whereby folding of the side and end walls with respect to said main panel will occur as the main panel is depressed into said opening, a depressible plunger operating against said main panel from above for depressing said main panel into said opening, means on said platform for engaging and locating a carton blank with its main panel above said opening, said means comprising elements having shoulders and downwardly extending edges and disposed on the platform so that the downwardly extending edges substantially coincide with the diagonal score lines in the corner connecting webs of the blank, said shoulders comprising horizontally extending portions for engaging and supporting the blank in a position above the upper surface of said platform and vertically extending portions for locating the main panel of said blank over the opening in said platform, said downwardly extending edges serving as score-breakers for the diagonal score lines in said corner connecting webs, means on said platform for initially engaging portions of said blank in restraining the fold-

ing of an opposite pair of walls thereof, whereby during the depression of said main panel, the other opposite walls begin to fold upwardly thereby starting the folding of said corner connecting webs in a position to lie against the first mentioned pair of opposite walls, said plunger having recesses at its ends to accept said corner webs in folded condition in a position lying against the first mentioned opposite pair of walls.

5. In a machine for setting up cartons of the type having a main panel, side and end walls articulated thereto, and diagonally scored corner connecting webs between the ends of the side and end walls respectively, a platform having an opening responding in size and shape to said main panel, whereby folding of the side and end walls with respect to said main panel will occur as the main panel is depressed into said opening, a depressible plunger operating against said main panel from above for depressing said panel into said opening, means on said platform for engaging and locating a carton blank with its main panel above said opening, said means comprising elements having shoulders and downwardly extending edges and disposed on said platform so that the downwardly extending edges substantially coincide with the diagonal score lines in the corner connecting webs of the blank, said shoulders comprising horizontally extending portions for engaging and supporting the blank in a position above the upper surface of the platform and vertically extending portions for locating the main panel of the blank over the opening in said platform, said downwardly extending edges serving as score-breakers for the diagonal score lines in said corner connecting webs, means on said platform for initially engaging portions of said blank and restraining the folding of an opposite pair of walls thereof, whereby during the depression of said main panel the other opposite walls begin to fold upwardly thereby starting the folding of said corner connecting webs in a position to lie against the first mentioned pair of opposite walls, said upper plunger having recesses at its ends to accept said corner webs in folded condition in a position lying against said first mentioned pair of opposite walls, and a lower plunger element having an upper position slightly above the upper surface of said platform but below the plane on which said blank is initially supported by said supporting elements, said lower plunger being depressible by the action of said upper plunger to a position below the plane of the upper surface of said platform, with both plunger elements in clamping relationship to said main panel, said lower plunger being guided for vertical reciprocation and spring pressed toward its upper position and provided with a lock to maintain its lowermost position during withdrawal of the upper plunger from the erected box.

6. In a machine for setting up cartons of the type having a main panel, side and end walls articulated thereto, and diagonally scored corner connecting webs between the ends of the side and end walls respectively, a platform having an opening responding in size and shape to said main panel, whereby folding of the side and end walls with respect to said main panel will occur as the main panel is depressed into said opening, a depressible plunger operating against said main panel from above for depressing said panel into said opening, means on said platform for engaging and locating a carton blank with its main panel above said opening, said means comprising elements having shoulders and downwardly extending edges and disposed on said platform so that the downwardly extending edges substantially coincide with the diagonal score lines in the corner connecting webs of the blank,

said shoulders comprising horizontally extending portions for engaging and supporting the blank in a position above the upper surface of the platform and vertically extending portions for locating the main panel of the blank over the opening in said platform, said downwardly extending edges serving as score-breakers for the diagonal score lines in said corner connecting webs, means on said platform for initially engaging portions of said blank and restraining the folding of an opposite pair of walls thereof, whereby during the depression of said main panel the other opposite walls begin to fold upwardly thereby starting the folding of said corner connecting webs in a position to lie against the first mentioned pair of opposite walls, said upper plunger having recesses at its ends to accept said corner webs in folded condition in a position lying against said first mentioned pair of opposite walls, and a lower plunger element having an upper position slightly above the upper surface of said platform but below the plane on which said blank is initially supported by said supporting elements, said lower plunger being depressible by the action of said upper plunger to a position below the plane of the upper surface of said platform, with both plunger elements in clamping relationship to said main panel, said lower plunger being guided for vertical reciprocation and spring pressed toward its upper position and provided with a lock to maintain its lowermost position during withdrawal of the upper plunger from the erected box.

7. The structure claimed in claim 6 including means in connection with the operating means for the upper plunger for releasing said lock.

8. The structure claimed in claim 7 wherein the locking and releasing means for said lower plunger comprises a cam plate pivoted on a base below said platform, a bracket on said lower plunger having a laterally extending pin engaging in a cam opening in said plate, said cam opening having a locking depression for said pin, the connection between said locking means and the operating means for said upper plunger being a connection between said operating means and said cam plate.

9. The structure claimed in claim 7 wherein the locking and releasing means for said lower plunger comprises a cam plate pivoted on a base below said platform, a bracket on said lower plunger having a laterally extending pin engaging in a cam opening in said plate, said cam opening having a locking depression for said pin, the connection between said locking means and the operating means for said upper plunger being a connection between said operating means and said cam plate, including a pull rod having a detent, a pin in connection with said cam plate to be engaged by said detent, and a support on said cam plate effective to prevent engagement of said detent with said pin excepting when said cam plate is in locking position.

10. The structure claimed in claim 7 wherein the locking and releasing means for said lower plunger comprises a cam plate pivoted on a base below said platform, a bracket on said lower plunger having a laterally extending pin engaging in a cam opening in said plate, said cam opening having a locking depression for said pin, the connection between said locking means and the operating means for said upper plunger being a connection between said operating means and said cam plate, including a pull rod having a

11

detent, a pin in connection with said cam plate to be engaged by said detent, and a support on said cam plate effective to prevent engagement of said detent with said pin excepting when said cam plate is in locking position, and spring means for urging said cam plate into locking position, the means for operating said upper plunger being a lever means, said pull rod having a connection with said lever means so as to be moved thereby, and said cam opening having a cam surface to control the rate of rise of said lower plunger when said lock is released.

11. In a device of the character described, a base, a platform supported above said base and having an opening of a size to receive the main panel of a carton to be erected, a lower plunger for movement in said opening, mounting means for guiding said lower plunger for vertical reciprocation, a cam plate pivoted on said base and having a cam opening, a bracket on said lower plunger having a laterally extending pin engaging in said cam opening, said cam opening being shaped to limit the upward movement of said lower plunger, and having a depression for engaging and locking said pin in the lowermost position of said lower plunger, and spring means for urging said cam plate to locking position.

12. The structure claimed in claim 11 including an upper plunger, pivoted lever means for operating said upper plunger, a pull rod pivoted to said lever means and having means for operating said cam plate.

13. The structure claimed in claim 12 wherein said cam plate bears a pin, said pull rod is provided with a detent for engaging said pin, and said cam plate is provided with an abutment for supporting said pull rod with said detent and pin out of engagement when said cam plate is in the position for the highest movement of said lower plunger, but inoperative to prevent said engagement when said cam plate is in position for locking said lower plunger.

14. In a machine of the character described, a platform having an opening to receive a main panel of a carton, a lower plunger reciprocating in said opening, an upper plunger adapted to engage said main panel and through it to depress said lower plunger, means for operating said upper plunger to engage said main panel and through it to depress said lower plunger, automatically acting locking means for said lower plunger in its lowermost position, and release means for said lock connected with the operating means for said upper plunger and effective on alternate strokes thereof.

15. In a machine of the character described, a platform having an opening therein constituting a female die, means above the platform and related to the opening therein for supporting out of contact with the platform an unfolded paper-board carton blank of a type having a main panel, side and end walls, diagonally scored corner connecting webs at the ends of said side and end walls and closure flaps on the outer edges of said side and end walls, means on said platform engaging said blank to retard initial folding of the said end walls, an upper plunger, means for operating said upper plunger so as initially to depress said blank between said supporting means so as to start an upward folding of the corner connecting portions, the side walls and their attached flaps, a retractable lower plunger in said opening for engaging the oppo-

12

site side of said main panel, and supporting said main panel during a further movement of said upper plunger in which said side and end walls and said corner connecting webs are fully folded with said side and end walls lying at least partially within said die, said supporting means comprising elements having shoulders and downwardly extending edges and disposed on said platform so that the downwardly disposed slanting edges substantially coincide with the diagonal score lines in the corner connecting webs of said blank, said shoulders comprising horizontally extending portions supporting the blank out of contact with the platform and vertically extending portions for locating the main panel of the blank over the opening in the platform, said downwardly slanting edges serving as score-breakers for the diagonal score lines in said corner connecting webs.

16. The structure claimed in claim 15 including means for locking said retractable lower plunger in its lowermost position whereby said upper plunger may be withdrawn from the erected carton leaving the carton in position in said female die for filling.

17. In a device including a support, a plunger and means for mounting said plunger for vertical reciprocation relative to said support, a cam plate pivoted to said support and having a cam opening, a bracket on said plunger having a laterally extending pin engaging in said cam opening, said cam opening being shaped to limit the upward movement of said plunger, and having a depression for engaging and locking said pin in the lowermost position of said plunger, and spring means for urging said cam plate to locking position, and a pull rod having means for operating said cam plate.

18. In a device including a support, a plunger and means for mounting said plunger for vertical reciprocation relative to said support, a cam plate pivoted to said support and having a cam opening, a bracket on said plunger having a laterally extending pin engaging in said cam opening, said cam opening being shaped to limit the upward movement of said plunger, and having a depression for engaging and locking said pin in the lowermost position of said plunger, and spring means for urging said cam plate to locking position, and a pull rod for operating said cam plate, said pull rod having a detent for engaging said pin, said cam plate being provided with an abutment for supporting said pull rod with said detent and pin out of engagement when said cam plate is in the position for the highest movement of said plunger, but inoperative to prevent said engagement when said cam plate is in position for locking said plunger.
